UNITED STATES PATENT OFFICE.

LEWIS B. DOMAN, OF EAST SYRACUSE, NEW YORK, ASSIGNOR TO THE AMPHION PIANO
PLAYER COMPANY, OF SYRACUSE, NEW YORK, A CORPORATION OF NEW YORK.

SELF-PLAYING MUSICAL INSTRUMENT.

1,269,406.

Specification of Letters Patent. Patented June 11, 1918.

Application filed July 21, 1918. Serial No. 780,350.

To all whom it may concern:

Be it known that I, LEWIS B. DOMAN, of East Syracuse, in the county of Onondaga, in the State of New York, have invented 5 new and useful Improvements in Self-Playing Musical Instruments, of which the following, taken in connection with the accompanying drawings, is a full, clear, and exact description.

10 This invention relates to certain improvements in self-playing musical instruments and refers more particularly to expression-controlling or tone-modifying apparatus, involving the use of a system of resistance 15 pneumatics arranged to oppose individually, or in combinations of two or more, the action of a tension regulator or governing pneumatic in a manner somewhat similar to that shown in my Patent No. 1,075-, 20 313, Oct. 7, 1913, except that the main object of my present invention is to provide for a wider range of expression or variations in tone-volume or force than has heretofore been practised with a relatively 25 small number of resistance devices.

In other words, I have sought to provide a simple and practicable tone-modifying unit capable of being installed in a small compact space in any self-playing musical 30 instrument, whereby the tone-volume or force of expression of any selected part of a musical composition may be progressively increased or diminished through the several standard divisions of "pianissimo" (pp), 35 "piano" (p), "mezzo-forte" (mf), "forte" (f) or "fortissimo" (ff), individually or collectively or through any combinations of such divisions.

Another object is to produce a relatively 40 large number of changes of force or air tension in the player action through the medium of various combinations of a relatively small number of resistance pneumatics as controlled by a correspondingly 45 small number of lines of perforations in a music sheet.

A further object is to incorporate in the same unit additional assistance pneumatics for accenting any selected note or notes of 50 any part of the composition which may be played in a degree lower than fortissimo (ff).

Other objects and uses relating to specific

parts of the apparatus will be brought out in the following description. 55

In the drawings—

Figure 1 is a perspective view of my improved expression device shown as operatively connected to its corresponding ducts of a tracker-bar for automatic action. 60

Fig. 2 is an enlarged face view of the same apparatus.

Fig. 3 is a sectional view taken on line 3—3, Fig. 2.

Figs. 4, 5 and 6 are face views of the 65 outer, intermediate and inner sections of the valve chest.

Fig. 7 is a diagrammatic view of a relatively small number of (in this instance four) lines of expression-controlling perforations in a music sheet arranged in their various combinations (in this instance sixteen) showing the relative size of the resistance pneumatics for each line of perforations of the different combinations thereof 70 as controlled by their corresponding combinations of perforations together with a graphic illustration of the relative degrees 75 of force or air tension produced by such combinations in a player action. 80

As illustrated this apparatus is made up as a unitary article of manufacture capable of being easily and quickly installed in any of the well known forms of self-playing pianos or other key-board instruments between the wind-inducing device and sound-producing action and comprises a wind-chest —1—, a valve-chest —2—, and a pneumatic governor —3— for regulating the air tension in said action. 85

Associated with the tension-governor —3— and valve chest —2— is a series of, in this instance four (4), resistance pneumatics —4—, —5—, —6— and —7— and a plurality of accenting pneumatics —8—, all of 95 which are controlled by suitable valves —9— and primary pneumatics —10— located within the valve-chest —2— as shown more clearly in Fig. 3.

The interior of the wind-chest —1— is divided by a partition —11— into lower and upper chambers or compartments —12— and —13— which are connected respectively to the wind-inducing device and sound-producing action in a manner presently described 100 and normally communicate with each other 105

- through a valve port —14— in said partition, the upper or low-tension chamber being connected to the tension-governing pneumatic —3— by a pipe or conduit —15— extending 5 through the partition —11— and bottom of the wind-chest so as to maintain constant communication between the governor-pneumatic —3— and sound-producing action. The lower or high-tension chamber —12— 10 is provided in one side with a valved-port —16— leading into a gate box having a passage —17— which, in turn, may be connected by a pipe —18— to any suitable wind-inducing device (not shown).
- 15 During the re-roll of a music sheet, it is desirable to cut off communication between the wind-inducing device and sound-producing action and for this purpose I have provided the port —16— with a normally 20 open pneumatic valve or gate —19— which may be connected to any normally closed atmosphere port as —19'— adapted to be automatically or voluntarily opened at the proper time for admitting atmospheric air to 25 said pneumatic valve for closing the same against its seat, it being understood that this pneumatic is normally under partial vacuum through the medium of a suitable bleed-hole therein.
- 30 The governing pneumatic —3— is rigidly secured by gluing or otherwise to the bottom of the wind-chest and its movable side is provided with a laterally extending arm —20— projecting under and beyond the 35 valve-chest —2— and connected by a retracting spring —21— to a tension-adjusting screw —22— which in turn is attached to an arm —23— on the top of the valve-chest to distend said governor-pneumatic, the tension 40 of the spring being adjusted so as to allow the governor-pneumatic to respond quickly to varying air tensions therein and also to prevent the closing of the valve for the port —14— tightly against its seat.
- 45 Coacting with the underside of the port —14— is a tension-governing valve —24— adjustably secured to a valve-stem —25— which extends through a guide gland —26— in the bottom of the wind-chest and rests 50 loosely on the upper face of the movable side of the governor-pneumatic —3— so that any variations in air tension affecting the movement of said pneumatic will produce a corresponding movement of the valve —24— 55 to control or govern the air tension in the sound producing action, the chamber —13— of the wind-chest being connected by a pipe —27— to the sound producing action not shown.
- 60 It will be observed that this valve opens with (not against) the air pressure which together with the spring —21— and its own gravity causes it to respond easily and quickly under varying degrees of air tension in the governing pneumatic —3—, it 65 being understood that any degree of air tension in the pneumatics —3— tending to close the valve —24— tightly causes a reduction of tension in such pneumatic and allows the spring to open the same and also 70 allows the valve sufficiently to maintain more or less open communication with the player action under a maximum degree of air tension in the wind-inducing device even when playing with the softest effect. 75
- The chamber —13— of the wind-chest may be connected by a pipe —27— to the sound-producing action (not shown) and also serves as a part of the connection between the chamber —12— and governor-pneumatic —3— for the purposes described. 80
- The resistance pneumatics —4—, —5—, —6— and —7— serve a purpose somewhat similar to the resistance pneumatics of my pending application previously referred to 85 in that they are connected to and are adapted to resist the closing action of the main governing pneumatic but vary in size or capacity and may be used in various combinations for producing a wider range 90 of variations of expression, force or tone-volume and are preferably supported in a plane below the main governing pneumatic by hangers or brackets —28— which are secured to the sides of the wind-chest, the 95 movable sides of said pneumatics being connected by flexible straps —29— to the adjacent movable sides of the pneumatic —3— so as to oppose the collapse of the latter with correspondingly varying degrees of 100 force when it is desired to increase the tone volume of any particular note or notes or part of a musical composition as effected by the corresponding perforations of the note sheet. 105
- These resistance pneumatics progressively increase in size or capacity from left to right (Figs. 1 and 2) and are operable individually or in combinations of two or more according to the emphasis which 110 is to be given to selected notes and for this purpose these pneumatics are connected by separate conduits —30— to corresponding valve chambers —31— in which the valves —9— are located, as 115 shown more clearly in Figs. 2 and 3.
- Each valve chamber is provided with an atmosphere port —32— and a suction port —33— aligned with each other in opposite sides of the valve chamber and between which the valve is adapted to play for alternately opening and closing said ports. 120
- The valve chest is also provided with an exhaust chamber —34— communicating with all of the suction ports —33— and common to all of the primary pneumatics —10— which are aligned with their respective valve chambers and are adapted to engage the stems of said valves as shown in Fig. 3. 125
- These primary pneumatics are preferably 130

mounted in the front side of the inner plate of the valve chest, the back side of said plate being provided with a series of air ducts —35— communicating with their respective primary pneumatics and connected by separate pipes —36— to any suitable means, such as extra ducts in the tracker bar or manually operated devices for admitting atmospheric air to any one or more of the primary pneumatics according to the degree of force or expression which may be required for any selected note or notes of a musical composition.

Each one of the channels —35— communicates through a relatively small bleed-hole —37— with the exhaust chamber —34— to assure the desired rapidity of action of the primary pneumatics and corresponding valves.

20 The accenting pneumatics —8— and —8—, as shown, are secured to the lower ends of the hangers or brackets —28— directly under the resistance pneumatics and connected by flexible straps to the governing pneumatics —3— and are also of different size or capacity and capable of being operated individually or collectively for resisting the closing action of said governing pneumatic and thereby accenting with varying 25 degrees of force any note or notes of a musical composition while playing in any degree of expression below fortissimo (ff) effects, thus producing three degrees of added force to that with which an accompaniment or other part is being played at the same time.

These resistance pneumatics are preferably operated automatically through the medium of extra ducts —38— in a tracker 40 bar —a— having the usual note ducts —a'—, the ducts —38— being controlled by extra perforations in a music sheet similar to that set forth in my pending application Serial No. 780,349 filed July 21, 1913, 45 but it is evident that they may be operated voluntarily by suitable manually controlled valves without departing from the spirit of this invention.

The accenting pneumatics —8— are also 50 connected by pipes —30'— to valve chambers —31'— in the valve chest and are controlled by valves —9— and primary pneumatics —10— similar to those previously described, the primary pneumatics being connected by conduits —36'— to the tracker ducts —38— for automatic action through the medium of corresponding perforations on the note sheet, or may 55 be controlled voluntarily by any suitable 60 device for admitting atmospheric air into the conduits —36'—.

The exhaust chamber —34— communicates with the chamber —12— of the wind chest through a passage —34'—, as shown 65 more clearly in Fig. 3.

In Fig. 7 of the drawings I have shown a portion of a music sheet —40— having in addition to its note perforations a relatively small number of (in this instance four) lines of perforations —b—, —c—, —d—, and —e— arranged side by side in close relation, parallel with each other and with the line of travel of the sheet and representing different degrees of expression or force with which certain notes corresponding to the note perforations which they control are to be played, the blank spaces in line with said perforations representing a different or normally lower degree of force than any of the perforations which, in this 80 instance, indicate gradually increasing degrees of force from left to right.

Each line of perforations is adapted to control one of a series, in this instance four, resistance pneumatics, —4—, —5—, —6—, and —7— indicated diagrammatically in Fig. 7 as associated with their controlling perforations —b—, —c—, —d— and —e— in the music sheet so as to show a relatively large number of variations in the degree of 90 force with which the selected parts of a musical composition may be played.

In order that this feature of my invention may be clearly understood I have shown the perforations arranged and combined so as 95 to produce sixteen (16) degrees of force and progressively increasing from top to bottom and have also shown each perforation or combination of perforations, and the different resistance pneumatics or combinations thereof which are brought into action simultaneously with the registration of such perforations or combinations with their respective tracker ducts —38— in the tracker bars —a— while the relative degrees of force 105 resulting from the use of the individual perforations and corresponding resistance pneumatics or the several combinations thereof are indicated by lines —X— arranged in a column at the extreme right 110 of the sheet opposite said perforations and corresponding pneumatics and combinations thereof.

The diagram, however, is only used to show more clearly the wide range of variations 115 of air tension which may be produced in the player action through the medium of a relatively small number of resistance pneumatics and it is evident that in actual practice the perforations —b—, —c—, —d— and —e— 120 will be arranged in the sheet to effect the desired expression of any selected part of the musical composition during the operation of playing as shown, for example, in my pending application Serial No. 780,349 125 previously referred to.

It must be remembered, however, that when no perforation is present in any of the lines —b—, —c—, —d— or —e—, the musical selection will be played with the 130

softest expression as controlled by the tension-regulating pneumatic —3— but, if it is desired to increase the force or expression, the sheet is provided with one or more of 5 such perforations arranged in such relation to the note or notes to be effected as to produce the desired effect of such note or notes at the proper time.

By connecting the movable sides of the 10 accent pneumatics —8— and —8— to the main governing pneumatic —3— through the medium of the flexible straps, it is evident that they may be brought into action either individually or collectively to 15 produce added resistance to the closing action of said governing pneumatic and its valve —24— so as to give added force to any one of the resistance pneumatics —4—, —5—, —6— or —7— which may be in 20 action or to the accompaniment or a melody which may be played under a predetermined force as determined by the resistance pneumatics.

Heretofore, so far as I am aware, when 25 an accent was required, it has been produced by suddenly throwing the full force of the air tension from the wind-inducing device into the sound-producing action but in the device forming the subject matter 30 of this application, this accent may be graded by bringing into action one or the other or both of the accenting pneumatics —8— and —8— which it will be seen are of different sizes or capacities and are capable 35 of producing three grades of force with but two perforations in the tracker bar and two lines of accent perforations in the music sheet.

This graded accent is accomplished by 40 connecting the accenting pneumatics to the main governing-pneumatic and permits the entire expression governing device including the pneumatics to be embodied in a single unit capable of being installed in a 45 relatively small space in any self-playing musical instrument and, in addition to the several advantages which I have previously 50 pointed out, it enables the connections between the expression-controlling unit and tracker bar to be very much simplified in that it permits of a wide range of variations in expression and accent with the use 55 of a relatively small number of extra ducts in the tracker bar, the tracker ducts for the resistance pneumatics for controlling the various degrees of force used for the accompaniment being elongated in the direction of travel of the sheet to cover two or more of the expression controlling perforations 60 in each line while the tracker ducts for the accent pneumatics are relatively short so as to embrace single perforations and produce the accent where desired.

What I claim is:

65 1. In a self-playing musical instrument,

tone-modifying means comprising a high tension chamber and a low tension chamber for communication, respectively with a wind-inducing device and a sound-producing action, said chambers having a connecting passage, a self-opening valve for said passage at the high tension side thereof, a pneumatic in open communication with the low-tension chamber only for partially closing said valve, pneumatic resistors for opposing the closing action of the first-named pneumatic, and means for selectively placing said resistors in communication with the high tension chamber. 70 75

2. In a self-playing musical instrument, 80 tone-modifying means comprising a high tension chamber and a low tension chamber having separate ports for connection, respectively, with a wind-inducing device and a sound-producing action, said chamber having a connecting passage, a self-opening valve for said passage opening into the high tension chamber, a pneumatic communicating with the low-tension chamber for partially closing the valve, pneumatic 90 resistors opposing the closing action of the first-named pneumatic, and means for selectively placing said resistors in communication with the high-tension chamber. 95

3. In a self-playing musical instrument, 100 tone-modifying means comprising a high-tension chamber and a low-tension chamber having separate ports for communication, respectively, with a wind-inducing device and a sound-producing action, said chambers having a connecting passage, a valve for said passage opening into the high tension chamber, a pneumatic communicating through a separate passage with the low-tension chamber for partially closing said 105 valve, pneumatic resistors opposing the closing action of the first-named pneumatic, means for selectively placing said resistors in communication with the high-tension chamber, and separate means for opening 110 and closing the high-tension port.

4. In a self-playing musical instrument, 115 tone-modifying means comprising a high-tension chamber and a low-tension chamber having ports for communication, respectively, with a wind-inducing device and a sound-producing action, said chambers having a connecting passage, a self-opening valve co-operating with the high-tension side 120 of said passage, a pneumatic communicating with the low-tension chamber only for partially closing said valve, pneumatic resistors opposing the closing action of the first-named pneumatic, means for selectively placing said resistors in communication with the high-tension chamber, and separate pneumatic means for opening and closing the high-tension port. 125

5. In a self-playing musical instrument, a wind chest having a high-tension chamber 130

and a low-tension chamber for communication respectively with a wind-inducing device and a sound-producing action, said chambers having a connecting port, a tension-regulating pneumatic in open communication with the low-tension chamber, a valve for said port controlled by the tension-regulating pneumatic and opening into the high-tension chamber outside of said pneumatic, a gate box communicating with the high-tension chamber and provided with a

port for communication with a wind-inducing device and a pneumatically operated gate in the gate box for closing communication between the last named port and high-tension chamber. 15

In witness whereof I have hereunto set my hand this 11th day of June, 1913.
